UNITED STATES PATENT OFFICE

2,013,909

HEATING SYSTEM

Alfred L. Browne, South Orange, N. J.

Application January 26, 1932, Serial No. 588,853

2 Claims. (Cl. 237—68)

This invention relates to heating systems and has for various of its objects to provide heating systems which are comparatively simple, inexpensive, economical, efficient, reliable, and flexible in that they may be readily adapted to the conditions of different installations and to different uses when installed. Other objects and advantages will appear as the invention is hereinafter disclosed.

10 Referring to the drawings, which illustrate what I now consider some of the preferred physical embodiments of the invention:

Fig. 1 is a sectional elevation of a venting appliance used in the various systems shown in subsequent views.

Fig. 2 is a detail sectional elevation of a part of the appliance shown in Fig. 1 with added features.

Fig. 3 is a detail sectional elevation of a part of the appliance shown in Fig. 1 with a modification in the air-venting control.

Fig. 4 is a detailed sectional elevation of a part of the appliance shown in Fig. 1, with an additional modification in the air-venting control.

25 Fig. 5 is a somewhat diagrammatic perspective view of one of my novel systems.

Fig. 6 is a detail sectional elevation of a differential seal particularly adaptable to the system shown in Fig. 5.

30 The venting appliances shown in Figs. 1 to 4, inclusive, are disclosed and claimed in my co-pending application Serial No. 526,892, filed April 1, 1931, in the United States Patent Office and entitled "Venting appliances for heating systems"

35 (now Letters Patent of the United States No. 1,847,053, Patented February 23, 1932), and in which I stated that the venting appliances there

shown and described may be employed in the heating system shown in Figs. 3 and 4 of my co-pending application Serial No. 294,078 (filed in the United States Patent Office on July 20, 1928) and described therein.

Since I now prefer to employ, in my systems hereinafter described, a venting appliance such as shown in Figs. 1 to 4, I shall now proceed to describe that venting appliance and some of the improvements or refinements therein which may be employed as desired. If desired, reference may be had to my said Patent No. 1,847,053 for a more complete description of the construction, advantages and operation of the venting appliances.

The venting appliance shown in Fig. 1 comprises a valve casing which is sealed except at three passages. One of these passages, 10, admits air, steam, and water of condensation to the

interior of the casing. Another of the passages, 11, discharges water of condensation from the casing. The other passage, 12, discharges air from the interior of the casing to the atmosphere. The valve casing shown comprises the body portion, 13, which is externally screw-threaded to receive the nut, 14, which holds the valve spud 15, tightly seated in the inlet end of the passage, 10, internally screw-threaded at the outlet end of the passage 11 to receive a discharge or return 10 pipe or conduit, and internally screw-threaded to receive the valve bonnet, 16, which is, in turn, internally screw-threaded to receive the valve member, 17, and the sub-bonnet, 18, the latter being provided with a screw-threaded vent opening, 19.

5 Means are provided within the valve casing, called into action by the entrance of steam into the casing, for closing the passage, 12. The means shown comprise the following structure: 20 the valve head, 20, adapted to seat in the valve seat provided in the valve member, 17, is secured to and carried by a sealed, hollow metallic container, 21, having a comparatively flexible bottom or diaphragm, 22, and containing a volatile 25 fluid. The bottom or diaphragm, 22, rests upon or abuts against a stationary support, 23. These parts are so designed and constructed as to operate as follows: in the absence of steam within the valve casing, the pressure of the volatile 30 fluid within the container, 21, is insufficient to force the diaphragm, 22, downwardly to such an extent as to move the valve head, 20, against its seat in the valve member, 17. However, when steam enters the valve casing, it contacts through 35 orifices, 33 and 34, with the thermostat, 21, 22, imparting heat thereto, causing the volatile fluid to expand and thus causing the diaphragm, 22, to bulge downwardly to such an extent as to close the valve head, 20, on its seat. The casing, 23, 40 which houses the thermostat, 21, 22, is threaded at its upper end and adapted to thread into the upper portion of bonnet, 16, as shown. The casing, 23, is provided with orifices, 33, at its upper portion, and also with orifices 34, through the 45 floor or bottom. These orifices, 33 and 34, permit the thermostat, 22, to be in restricted communication with the interior of the valve casing 13, 16. The orifices 33 may be eliminated entirely and one or more orifices 34 only may be 50 used. The casing, 23, also controls or limits lateral movement of the member, 21, accurately and to a minimum extent.

55 Means are provided also for preventing the escape of water of condensation from the valve cas-

ing through the passage, 12. The container, 21, above described, acts not only as a thermostat but serves also as a float. If and when water collects and its level rises within the valve casing, 5 this float, 21, is raised by the rising water and forces the valve head, 20, firmly against its seat before the water level reaches the passage, 12.

There are also provided means for preventing the entrance of air into the valve casing through 10 the passage, 12. One form of such means is shown in Fig. 1, and is constructed as follows: the upper end of valve member, 17, is provided with an annular rib or seat, 24, upon which a valve disc, 25, rests. This valve disc permits the escape of air from the interior of the casing, 13, 16, to atmosphere through the passages, 12 and 19, but when the pressure within the casing, 13, 16, is below atmospheric pressure, the valve disc, 25, prevents entrance of air into the casing, 13, 20 through the passage, 12.

The valve disc, 25, is made of the desired thickness and weight for the purpose of providing any desired air venting resistance.

By using discs, 25, each of the properly designed weight for its radiator, the steam circulation within the respective radiators can be balanced so that the complete heating of each radiator can be effected at approximately the same time, regardless of the difference in size of the 30 radiators or their respective nearness to or distance from the boiler.

Within the valve casing, 13, are provided also pressure responsive means for preventing the entrance of water, air, or steam through the passage, 16, back into the radiator. These means include a specially-constructed check valve, consisting of a body or seat member, 26, to which there is pivotally connected a valve head or clapper, 27, at 28. The neck of the check valve body, 26, protrudes through an annular orifice in the valve casing, 13. The neck of the check valve body, 26, is threaded to receive a lock nut, 30, in order securely and rigidly to fasten the entire check valve member in place. A gasket, 29, may be provided in case the contacting surfaces between the valve body, 13, and the shoulder of the extension neck of the check valve casing, 26, are not machined to an accurate, tight fit.

The check valve body is provided with a duct or port, 31, the upper end of which is parallel to and adjacent the spud port or passage, 10. The lower end of the duct 30 terminates at the annular rib or check valve seat, 32. It will be observed that the upper end of check valve port, 30, and the lower end of check valve port, 30, are at two different levels, the outlet end of the duct 30 being below the inlet thereto.

The device illustrated in Fig. 1 possesses also other desirable features not yet described. Thus, 60 a flat strip 35 of spring brass, or other suitable material, is sprung and seated at its opposite ends in undercut slots in the member 17 to prevent dislodgement of the disc or clap 25 but yet to permit its unseating to permit controlled escape 65 of air from the port 12 to the atmosphere. Furthermore, the member 17 is shown provided with lateral holes or apertures 36 to discharge any drops of condensate laterally, or radially, and then downwardly to the metallic evaporating 70 floor 37. When steam first enters the casing 13, 16, particularly if the radiator to which it is connected is turned on suddenly while pressure is carried, there may be a few drops of condensation formed on the general interior surfaces of 75 the entire venting appliance. Should one or two

drops of this condensate formed on the valve members 17, 20, be discharged through the valve orifice 12, effective evaporation of this small quantity of condensate is achieved without any discharge thereof through the final venting port 5 13.

My venting appliance may also be provided with means for muffling the expulsion of air which commonly and ordinarily produces a hissing sound in many forms of air-venting appliances. One form of such muffling means is shown in Fig. 2 in which the sub-bonnet 18 is provided with two annular screens, 38 and 40, of perforated sheet brass or other reticulated metal, between which is confined a quantity of pebbles 39, 15 or other durable, steam-resistant, and heat-resistant particles. These provisions permit the escape of air but muffle the sound ordinarily incident to such escape.

According to the construction shown in Fig. 3, 20 the casing portion 16A corresponds to the casing portion 16 in Fig. 1 except that the screw threads for the sub-bonnet 18A are provided on the outside instead of the inside. The member 17A corresponds to the member 17 of Fig. 1 but is 25 somewhat modified in construction as will now be noted. The member 17A, having the port 12A corresponding to the port 12 in Fig. 1, is internally screw-threaded in order adjustably to receive a screw 41 which is provided with a T-shaped passage 43 communicating with the port 12A. The upper end of the screw 41 is conical to serve as a valve member and is provided with a slot for purposes of adjustment. The sub-bonnet 18A, provided with the tapped opening 35 19A corresponding to the hole 19 in Fig. 1, serves to grip between it and the upper end of the bonnet 16A, a flexible metallic diaphragm 125 having a valve member 44 adapted to be closed by the member 41. By inserting a screw driver through 40 the opening 19A into the slot in the head of the screw 17A, and turning it in one direction or the other, the position of the valve member 17A with respect to the valve member 44 may be adjusted and set as desired. By virtue of this adjustment the time of opening and closing and the rate of air discharge through the valve 17A—44, with respect to the steam pressure may be regulated, adjusted, and set, as desired. Thus the heating of each radiator with respect to another, or others, can be readily controlled and at will.

In Fig. 4 the sub-bonnet 18B, having the opening 19B, corresponds to the sub-bonnet 18 of Fig. 1 or 18A of Fig. 3; the member 44A corresponds to the housing for the valve 25 as in Fig. 1 and serves also as a valve member corresponding to the valve member 44 of Fig. 3. In the arrangement shown in Fig. 4, the valve 41—44A is normally open and closes only when the pressure within the casing 16A is sub-atmospheric. Being normally open, air can vent freely through these valve members 41—44A and lift the disc 25 and vent through the port 19B. When the pressure within the casing 16A is sub-atmospheric, i. e. a partial vacuum, the disc 25 closes as previously described in connection with Fig. 1. However, atmospheric pressure exerted through the vent port 19B upon diaphragm 125 causes the whole member 44A to drop slightly 70 and seat securely on the fixed valve head 41, giving under vacuum conditions of operation, the tight venting valve feature as described in connection with Fig. 3.

In heating system hereinafter described, one 75

or another form of the venting appliances or traps above described (Figs. 1 to 4) is employed, preferably one for each radiator, such venting appliance or trap being in each instance indicated by the reference numeral 16. The heating system will be found to comprise: a boiler, radiators, a steam supply system for conveying steam from the boiler to the radiators, a sealed return system for conveying condensate from the radiators to the boiler, and pressure of elastic fluid in the sealed return system being slightly less but substantially the same as that in the steam supply system; and a plurality of traps (16) each individual to a radiator (preferably there are as many traps 16 as there are radiators but in some cases there may be more radiators than there are traps 16) for venting air from its corresponding radiator and for returning condensate to a sealed return system and thence to the boiler. Each of the traps 16 receives steam, air, and/or condensate from a radiator through its inlet port 10, discharges air to atmosphere through the discharge port 12, discharges condensate through the outlet port 11 to the sealed return system, prevents steam from escaping to atmosphere, etc.

I shall now proceed to describe in greater detail the form of my system shown in Fig. 5.

The boiler 70 has connected thereto a steam supply system, comprising the steam main 71, through which the boiler supplies steam, and a sealed return system comprising a wet pressure return line 72 (below the level of the steam main 71), through which condensate is returned to the boiler. A riser 74 connected through a steam branch connection 73 to the main 71 supplies steam from the main 71, through steam branch connections 75, to radiators 77, 77, on an upper level or floor. Each radiator 77 is shown provided with a radiator inlet valve 76, of usual construction, to control the supply of steam to the radiator through the steam branch connection 75. The radiators 77, last referred to, are each provided with a venting appliance or trap 16 which discharges its condensate through a return branch connection 78 into a return riser 79, thence through a return riser branch connection 80 (in which a differential loop seal 81 is interposed) into the steam riser branch connection 73. A suitable form of differential loop seal 81 is shown in Fig. 6 to be described in greater detail. A steam branch connection 82 supplies steam from the main 71 to a radiator 77 on the first floor; the last mentioned radiator, as in the case of the upper floor radiators 77, 77, being provided with a radiator inlet valve 76. The first floor radiator 77 discharges its condensate into its trap or venting appliance 16, thence through a return branch connection 83 (in which a differential loop seal 81, similar to the other such device shown in Fig. 6, is interposed), thence into the steam supply branch connection 82.

The differential loop seals 81 are, as stated, alike in construction and one of them is shown in detail in Fig. 6. This device comprises a casing 81 which is divided into two compartments by a partition 61 so that the bottom of the partition forms a somewhat slight water seal. The partition 61 is shown provided with a metering orifice 62.

The system shown in Figs. 5 and 6 is constructed and designed to operate substantially as follows:

When steam is generated in the boiler 70 it flows through the steam main 71, thence through

the riser branch connection 73 to the steam riser 74 and thence through the steam branch connections 75 and through the radiator inlet valves 76 into the radiators 77. Air is expelled from each radiator 77 directly to atmosphere through its trap 16. Condensate is freely discharged through each trap 16 into the return branch connections 78, return risers 79, thence by gravity through the radiator branch connection 80 to the differential seal 81 and thence from the differential seal back into the steam riser branch 73. At or about the same time, steam circulation is established in the same manner in the first floor radiator through the branch 82, inlet valve 76, the radiator 77, venting air at the corresponding trap 15 16, and returning condensate through the trap 16 into the return branch 83, the condensate flowing through the differential seal 81 back into the steam supply branch 82. The condensate from the radiators flows by gravity from the steam riser branches 73 and 82 back into the steam main 71 in the same manner as in a standard one-pipe system of heating. The steam main 71 pitches or slopes in direction as indicated by the arrows and drops into the wet pressure return 72. (If desired, this return main 72 could be situated just below the steam main 71 and run as a dry pressure return main, dropping wet at or close to the boiler 70. An advantage of this system is the use of the steam supply main 71 also as a part of the return system; this being made possible, in this instance, by the differential loop seals 81 which function as will be described.

Steam, in passing from the steam main 71 to the steam risers 74 and the first floor steam branch 82, is prevented by this device 81 from circulating through the return branches 80 and 83 and the return riser 79 to the trap 16, without a predetermined pressure drop.

Steam from the steam main 71, is prevented from flowing freely through the seal 81 by the existence at its lower portion of a water seal. At the upper portion of the device 81, steam flows through the metering orifice 62 which restricts materially its flow to and through the return branches and risers 79, 80, 83, to the radiator trap 16. If, for instance, the differential produced by the metering orifice 62 is sufficient to cause a difference in pressure of two ounces between the steam main 71 and the return risers and connections 79, 80, 83, then there will be a corresponding head of water on one side of the partition 61 (as shown in Fig. 6) for this particular pressure differential. It would amount, in the case assumed, to a hydrostatic head of water of about three and one-half inches. If this differential is more than the differential of the check valve incorporated in the trap 16, then when any particular radiator 77 is turned on while steam pressure in the entire heating plant is being carried, its air content will be rapidly eliminated through its trap 16 directly to atmosphere due to the accelerating effect of the differential seal 81 which produces a pressure differential between the two sides of the radiator greater than the pressure differential created by the slight resistance of the delicately balanced check valve incorporated in the trap 16. If the return connections 79, 80, 83 connected back directly into the steam branch connections 73, 82, without this device 81 or an equivalent device, then the pressure within the casing of the trap 16 would be identical with the pressure in the steam branches 73, 83, riser 74 and branches 75. Venting of air 75

from the radiators (particularly if the valves 76 were suddenly turned on while steam pressure was being carried) under this condition would be much slower inasmuch as the steam supplied to the casing of the thermostatic trap 16 (and shutting its air vent valve) would be identical in pressure with the steam attempting to enter the radiator. The only force then in favor of steam entering the radiator would be the static head of air offsetting the very delicate resistance of the check valve within the trap 16.

Referring again to the differential loop seal 81 (Fig. 6), it will be further noted that if the differential created by the orifice 62 is greater than necessary, steam can and will break through the water seal whenever its pressure is greater than the hydrostatic head of the seal. Also, condensate, flowing by gravity through the return connection (80 or 83) and into the loop seal, can readily pass through the lower portion of the seal and back into the steam main 71 whenever the pressure differential between the steam main 71 and the return connections 80, 83 is less than the hydrostatic head of water caused by the seal.

In the system illustrated in the drawings, I have shown two radiators upstairs and one radiator on the first floor. This was done for convenience and simplicity in disclosure. It will, of course, be understood that more radiators may be employed on the upper floors or levels, with similar connections, and that more radiators may be employed on the first floor or lower level, with similar connections.

It will be noted that my invention is a gravity return system of heating in which all three systems of basement mains, i. e. steam mains, dry return mains, and (wet or dry) pressure drip return mains, may be used. Boiler return traps, pressure equalizing loop seals, pumps, air venting traps or devices, or other similar apparatus, may be dispensed with as unnecessary. The dry return may be dispensed with and the return risers may connect into the (wet or dry) pressure return, or they may connect back into the steam mains, either sealed wet or dry. These various forms of piping are possible as there is normally no air flow in the return piping system according to my invention, and there is no substantial pressure differential between the supply system and the return system. The condensate flows freely back to the boiler by gravity and none accumulates in the system above the water line of the boiler except to the extent of the small hydro-

static head corresponding to the slight differential pressure existing between the supply and return.

In accordance with the provisions of the patent statutes, I have herein described the principle of operation of my invention, together with the apparatus which I now consider to represent the best embodiments thereof, but I desire to have it understood that the apparatus disclosed is only illustrative and that the invention can be carried out by other means. Also, while it is designed to use the various features and elements in the combinations and relations described, some of these may be altered and others omitted and some of the features of each modification may be embodied in the others without interfering with the more general results outlined, and the invention extends to such use within the scope of the appended claims.

What I claim is:

1. A heating system comprising in combination, a boiler, a plurality of radiators, a steam supply system for conveying steam from the boiler to the radiators, a sealed return system for conveying condensate from the radiators by gravity to the boiler, the pressure of elastic fluid in the sealed return system being substantially the same as that in the supply system, a plurality of check valves each located in a corresponding return branch connection of each of said radiators for permitting the discharge of fluid from its radiator, and automatic air-venting means in each of the last mentioned return branch connections on the discharge side of the check valve in that branch connection. 35

2. A heating system comprising in combination, a boiler, a plurality of radiators, a steam supply system for conveying steam from the boiler to the radiators, a sealed return system for conveying condensate from the radiators by gravity to the boiler, the pressure of elastic fluid in the sealed return system being substantially the same as that in the supply system, a plurality of check valves each located in a corresponding return branch connection of each of said radiators for 40 permitting the discharge of fluid from its radiator, and a thermostatic air vent in each of the last mentioned return branch connections on the discharge side of the check valve in that branch connection, each of said thermostatic air vents 50 being always open in the absence of steam or liquid around it.

ALFRED L. BROWNE.
